UNITED STATES PATENT OFFICE

130,415

DESIGN FOR AN AUTOMOBILE ACCESSORY DISPLAY RACK OR SIMILAR ARTICLE

William Hynes Pitner, Granville, and James
Jones, Edwin Eberts, and Vance S. Firestone,
Newark, Ohio

Application August 13, 1941, Serial No. 102,820

Term of patent 7 years

To all whom it may concern:

Be it known that we, William Hynes Pitner, James Jones, Edwin Eberts, and Vance S. Firestone, citizens of the United States, residing at Granville, Newark, Newark, and Newark, respectively, in the county of Licking and State of Ohio, have invented a new, original, and ornamental Design for an Automobile Accessory Display Rack or Similar Article, of which the following is a specification, reference being had to the accompanying drawings, forming a part thereof.

Figure 1 is a perspective view of an automobile accessory display rack or similar article, showing our new design;

Figure 2 is a side elevational view thereof, on a reduced scale; and

Figure 3 is an end elevational view thereof, the scale of the figure corresponding to that of Figure 2.

We claim:

The ornamental design for an automobile accessory display rack or similar article, as shown.

WILLIAM HYNES PITNER.
JAMES JONES.
EDWIN EBERTS.
VANCE S. FIRESTONE.
